UNITED STATES PATENT OFFICE.

HARRY W. DARNEY, OF BALTIMORE, MARYLAND, ASSIGNOR, BY DIRECT AND MESNE ASSIGNMENTS, TO D. R. S. COMPANY, OF BALTIMORE, MARYLAND.

CIGARETTE-FIRE SNUFFER.

Application filed September 12, 1927. Serial No. 219,070.

This invention has reference to ash receivers and aims to provide novel means whereby the lighted end of a cigarette may be pinched to smother the light after the cigarette has been smoked, thereby eliminating the offensive odor arising from a smoldering cigarette.

An important object of the invention is to provide a device of this character which 10 may be actuated by the contact of the fingers holding the cigarette, by exerting a slight downward pressure on the device as the cigarette is being guided between the jaws of the device.

15 Another object of the invention is the provision of means whereby the device will automatically return to its normal position after the light of a cigarette has been extinguished, thereby releasing the cigarette 20 so that it may be deposited in the ash tray of which the device forms a part.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:

Figure 1 is a plan view of an ash receiver equipped with a device constructed in accordance with the invention.

Figure 2 is a front elevational view thereof.

Figure 3 is a sectional view taken on line 3-3 of Figure 2.

40 Figure 4 is a front elevational view illustrating the spring arms as moved in the act of clamping the lighted end of a cigarette therebetween.

Referring to the drawing in detail, the 45 reference character 5 indicates an ash receiver which may be of any desired construction, the same being however preferably formed with a flange such as indicated at 6.

50 Secured to the flange 6, and arranged at opposite sides of the ash receiver are arms 7 which are formed preferably of spring steel, the same being curved upwardly from the ash receiver, as clearly shown by Figure

55 2 of the drawings, where they are provided

with right angled extremities 8 that define jaws for purposes to be hereinafter more fully described.

Mounted for sliding movement on the arms 7 is a guide member indicated generally by the numeral 9, the guide member being provided with a curved base 10 which has laterally extended fingers 11 designed to be bent under the arms 7 as clearly shown by Figure 3 of the drawing, the fingers being bent in such a way that slight movement of the spring arms 7 under the fingers, will be permitted.

This guide member 9 also embodies an upstanding tubular member 12 which is provided with a tapered flange 13 defining a finger rest to be engaged by the fingers of the person using the device, so that the guide and cigarette supported within the guide may be pressed downwardly to actuate the 75 arms, to the end that the jaws will be brought into cooperative relation with each other.

In the use of the device, should it be desired to extinguish the light of a cigarette, 80 the lighted end is forced into the guide member so that the burning end of the cigarette will lie between the jaws 8, whereupon the guide is pressed downwardly in a manner as shown by Figure 4, with the result that the jaws are moved towards each other, as the spring arms 7 bend downwardly, pinching or mashing the lighted end of the cigarette, extinguishing the fire.

After the fire has been extinguished, it is 90 obvious that the cigarette may be removed from the guide and dropped into the ash receiver.

I claim:

1. A device for extinguishing the fire of a 95 lighted cigarette, embodying a supporting surface, spring arms extending upwardly from the supporting surface, cooperating jaws at the outer ends of the arms, a guiding member mounted on the arms and through 100 which a cigarette may be passed, and said guiding member adapted to be pressed to cause the jaws to move together to pinch the cigarette positioned in the guiding member.

2. A device for extinguishing the fire of a 105 lighted cigarette, embodying a supporting member, arms secured to the supporting member and having jaws at their inner ends, said jaws adapted to normally lie in spaced relation with each other, a guiding member 110

supported by the arms and through which a cigarette is extended, said guiding member adapted to guide the cigarette to the jaws, and said jaws adapted to move towards each other to grip the cigarette extended through the guiding member.

3. A device for extinguishing the fire of a lighted cigarette, embodying an ash tray, upwardly and inwardly curved arms formed of 10 spring steel material and secured to the ash tray, said arms having right angled downwardly extended end portions defining jaws, said jaws adapted to normally lie in spaced relation with each other, a guiding member 15 supported by the arms, said arms adapted to move through the guiding member when the guiding member is depressed, said guiding member adapted to guide a cigarette to the jaws, when a cigarette is positioned within 20 the guiding member, and said jaws adapted to clamp the cigarette to extinguish the fire of the lighted cigarette.
4. A device for extinguishing the fire of a lighted cigarette, embodying a supporting 25 member, arms extending upwardly from the supporting member and having right angled downwardly extended ends defining jaws, a guiding member supported on the arms, said

guiding member including a base having inwardly bent fingers embracing portions of 30 the arms to slidably support the guiding member on the arms, a tubular portion forming a part of the guiding member and through which a cigarette is extended as the cigarette is passed to the jaws, and said jaws 35 adapted to pinch the lighted end of a cigarette positioned within the guiding member when the guiding member is depressed.

5. In a device for extinguishing the fire of a lighted cigarette, a supporting member, 40 spring arms extending upwardly from the supporting member, jaws formed at the inner ends of the arms, a guiding member supported on the jaws and adapted to guide a cigarette extended therethrough, to the 45 jaws, a flange on the guiding member to be engaged by the fingers of the operator to press the guiding member and jaws downwardly, and said jaws adapted to pinch a cigarette forced through the guiding member when pressure is brought to bear on the guiding member.

In testimony that I claim the foregoing as my own, I have hereto affixed my signature.

HARRY W. DARNEY.
